Primary Examiner — John R Yeh*(74) Attorney, Agent, or Firm* — Fitzgerald IP Law; John K Fitzgerald(57) **CLAIM**

The ornamental design for a toy ride, as shown and described.

DESCRIPTION

FIG. 1 is a perspective view of a toy ride showing my new design;

FIG. 2 is a front view thereof;

FIG. 3 is a rear view thereof;

FIG. 4 is a top plan view thereof;

FIG. 5 is a bottom view thereof;

FIG. 6 is a left side view thereof; and,

FIG. 7 is a right side view thereof.

The broken lines shown are included for the purpose of illustrating portions of the article which form no part of the claimed design.
